UNITED STATES PATENT OFFICE.

JAMES BUCKLER, OF PHILADELPHIA, PENNSYLVANIA, ASSIGNOR, BY MESNE ASSIGNMENTS, TO JOHN M. RUSSELL, OF WORCESTER, MASSACHUSETTS.

WOVEN MULTIPLE-PLY FABRIC.

SPECIFICATION forming part of Letters Patent No. 574,387, dated January 5, 1897.

Application filed November 20, 1895. Serial No. 569,483. (Specimens.)

To all whom it may concern:

Be it known that I, JAMES BUCKLER, a citizen of the United States, residing at Philadelphia, in the county of Philadelphia and State 5 of Pennsylvania, have invented certain new and useful Improvements in Woven Multiple-Ply Fabrics, of which the following is a full, clear, and exact description, reference being had to the accompanying drawings, forming 10 a part of this specification.

This invention relates to woven multiple-ply fabrics, having reference more especially to two-ply ingrain carpet, my object being to produce a thoroughly-bound fabric free from 15 "pockets" or unbound portions between the plies and in which the threads of one ply shall not appear on the face of the other, excepting when such threads are thrown thereto in the formation of a figure. This result is 20 attained by the crossing, in the interior of the fabric, of the warp-threads of the respective plies, as will hereinafter appear.

In the accompanying drawings, illustrating my improved woven two-ply fabric, Figure 1 25 is a diagram showing the binding, by means of a single warp, of each opposite ply or face. Fig. 2 is a like view in which the binding is effected by means of both warps in each ply crossing each other in alternate succession. 30 Fig. 3 is a modification in which a supplemental weft-thread is employed. Fig. 4 is a diagrammatic sectional view of the four warp-threads, and showing also the weft-threads, whereby the disposition of these threads in 35 the fabric illustrated in the other figures may be more readily understood.

In the ordinary mode of weaving two-ply fabrics, such as carpets, the pair of figure-wefts are mated with the opposite pair of 40 ground-wefts, and owing to the manner in which the warps are usually operated a figure-weft always appears upon one face of the fabric, while its ground-weft mate always appears upon the opposite face, and thus 45 the fabric is usually woven with the mate wefts opposite each other, or, in other words, with the pair of figure-wefts side by side on one face or ply of the fabric and the ground-wefts side by side on the other ply or back 50 of the fabric, the only variation possible be-

ing an alternative of this order due to what is well known as a "shot-about" effect. In this usual mode of weaving two-ply fabrics, and in all other modes, as far as I know, each figure-weft is always bound by a warp-thread 55 of its own color, the four warps and the four wefts being usually of the same colors, and the warp-threads are so operated that they directly bind together opposite weft-threads, figure-wefts to figure-wefts and ground-wefts 60 to ground-wefts, by warp-threads corresponding thereto in ground or figure colors; and this binding is not opposite each pair or each alternate pair of weft mates, but usually at long intervals, thereby forming pockets or 65 spaces, being the faces of the fabric not bound or united together.

In carrying out my invention in one form thereof the four warp-threads are so disposed in the weaving that the pair of warp-threads 70 of each ply or face binds only its own pair of weft-threads on each face, one of the binding or warp threads of one ply crossing the corresponding thread of the other ply in the interior of the fabric at points directly intermediate opposite wefts of the respective plies, 75 thereby effecting a uniform binding together of the two plies throughout the length and breadth of the fabric. A fabric thus constructed is not only free from pockets or unbound portions between the plies, but the threads of one ply do not appear on the face of the opposite ply. Such a fabric is represented in Fig. 1 of the drawings, wherein A 80 B represent the respective plies, a a' being 85 the warp-threads and a² a³ the weft-threads of the upper ply and b b' being the warp-threads and b² b³ the weft threads of the lower ply.

It will be observed that the warp-threads a 90 and b of the respective plies are crossed upon each other in the interior of the fabric with the effect stated. This is attained by moving the threads a and b laterally in opposite directions during the weaving of the fabric, one set 95 of threads a being up and the other, b, down. The threads a are then let down below the threads b, whereupon the threads b are lifted, which latter threads thus pass under the threads a, and in consequence the warp- 100

threads are crossed. The weft-threads are shot into the succeeding sheds in the usual manner.

A loom designed to handle the threads in the manner just described forms the subject of an application for Letters Patent of the United States filed by me February 3, 1896, Serial No. 577,856.

In Fig. 2 is represented a fabric in which 10 the binding is effected by the crossing of both pairs of opposite warp-threads, one thread of one pair with one thread of the opposite pair, in alternate succession. This is attained by moving both pairs *a b* and *a' b'* similarly to 15 the single pair *a b* in the first-described construction.

If it be desired to use an additional weft-thread *c*, that is to say, a thread differing in color from the other wefts in the fabric, the 20 same may be run or floated between the crossing or tying points of the opposite warp-threads and thrown to either face of the fabric at any desired point or points thereon. (See Fig. 3.)

25 The invention above described is particularly applicable to plain or unfigured two-ply fabrics with different-colored faces, say one red and the other green, in view of the fact that the warp of one ply will not appear on the 30 face of the opposite ply, which result, so far as I am aware, has never heretofore been attained.

In the weaving of a figured fabric wherein 35 the warp-threads of the respective plies are crossed and bound together in the manner described the figuring-warp of one ply is thrown onto the face of the opposite ply so as to effect the weaving of the desired pattern, but such figuring-warp at no other time appears upon 40 the opposite face of the fabric.

Having thus described my invention, what

I claim as new, and desire to secure by Letters Patent, is—

1. A woven multiple-ply fabric wherein the weft-threads of each ply are bound into the 45 fabric by their warp-threads, warp-threads of one ply being crossed with those of another ply at points directly intermediate opposite wefts of the respective plies, substantially as described.

2. A multiple-ply fabric wherein the weft-threads of each ply are bound into the fabric by their warp-threads, one of the pair of warp-threads of one ply being tied or bound into the fabric by the crossing thereon of one of 55 the warp-threads of the opposite ply at points directly intermediate opposite wefts of the respective plies, substantially as described.

3. A woven multiple-ply fabric wherein the weft-threads of each ply are bound into the 60 fabric by their warp-threads, the warp-threads of one ply being crossed with those of another ply at points directly intermediate opposite wefts of the respective plies, and a supplemental weft-thread run into the fabric, sub- 65 stantially as described.

4. A multiple-ply fabric in which the weft-threads of each ply are bound into the fabric by their warp-threads, one of the pair of warp-threads of one ply being tied or bound into 70 the fabric by the crossing thereon of one of the warp-threads of the opposite ply or face, and a supplemental weft-thread run into the fabric, between the faces thereof, substantially as described.

In testimony whereof I have hereunto affixed my signature this 18th day of November, A. D. 1895.

JAMES BUCKLER.
